UNITED STATES PATENT OFFICE.

CHARLES W. PEOBLE, OF TROY, NEW YORK.

FOLDING BEDSTEAD.

SPECIFICATION forming part of Letters Patent No. 352,568, dated November 16, 1886.

Application filed April 7, 1886. Serial No. 198,105. (No model.)

To all whom it may concern:

Be it known that I, CHARLES W. PEOBLE, of Troy, in the county of Rensselaer and State of New York, have invented new and useful 5 Improvements in Folding Bedsteads, of which the following is a specification.

My invention relates to improvements on that class of folding bedsteads in which are combined a stationary portion and a movable 10 bed-frame hinged thereto by means of a shifting pivot, and provided with weights arranged to counterbalance the excess of weight at the foot of said bed-frame.

The object of my improvements is to provide 15 a suitable friction device for easing the shock or strain commonly produced when the bed-frame is being turned in either direction, but especially at the terminal point of its movement in either direction. This object I attain by means 20 of the mechanism illustrated in the accompanying drawings, which are herein referred to and form part of this specification, and in which—

Figure 1 is a vertical section of the standing 25 frame of my bedstead with the movable bed-frame in its extended position, shown in side elevation; Fig. 2, a like view with the bed-frame turned up in its closed position; Fig. 3, a rear elevation of Fig. 1, and Fig. 4 30 an enlarged longitudinal section of the head of the movable bed-frame.

As represented in the drawings, A is the standing frame of the bedstead, which forms the head-board of the bed when in use, and 35 which is provided with side pieces, a, which extend forward to form a recess, into which the movable bed-frame enters when turned up in the position shown in Fig. 2; B, the movable bed-frame, which is adapted to swing up 40 and down in the standing frame A, and for that purpose is provided at each side with segmental gears b, which engage in gear with the racks a', (shown in dotted lines in Figs. 1 and 2,) which are fixed at the bottom of pockets, 45 (also indicated by dotted lines in Figs. 1 and 2,) into which said segmental gears are inserted by removing the detachable blocks a'', which are doweled to the side pieces, a, to form a flush finish therewith. The segmental gears 50 are of sufficient curvature to permit the bed-

frame B to swing through an arc of at least ninety degrees, or so that said bed-frame can be turned from a horizontal position to a vertical one, and it will be seen that by means of the segmental gear and rack the center of motion will be shifted forward by turning the bed-frame down into its horizontal position, and rearward by turning said bed-frame into its vertical position.

At the head of the bed-frame B, beyond the center of motion of the segmental gears b, a transverse box or chamber, C, is formed for containing the weights C', for counterbalancing the excess of weight which must come at the foot of the bed-frame B, and to render said counter-weights effective when said bed-frame is at or approaching its vertical position the center of gravity of said weights should lie to the rearward of the center of motion of the segmental gears b when the bed-frame is in its vertical position.

In order to ease the strain or shock caused by the movable bed-frame in approaching and completing the end of its movement in either direction, I fix at each side of the head of said bed-frame the friction rubber blocks D, which I preferably render adjustable by means of the set-bolts d, whereby said blocks may be forced outwardly. Said blocks are adapted to bear against the curved friction-plates E, of metal 80 or other suitable material, which are secured to the side pieces, a, of the standing frame, and which are so arranged as to produce the greatest degree of friction when the bed-frame B is at or near the termination of its motion in either direction, and to accomplish this purpose the plates E should be made slightly thicker near each end, or so that the faces of said plates should be slightly closer together at the ends than at the intermediate points, and the frictional pressure can be readily increased or diminished, as occasion requires, by turning the set-bolts d out or in to meet the requirements of the case.

Being aware that folding bedsteads have heretofore been made with friction-bars having one end pivoted to the standing frame, the swinging end of said friction-bars being forced forward by means of a spring, whereby the degree of frictional contact was limited to the 90

power obtained from said spring, I do not claim the use of swinging friction-bars; but

What I claim as my invention is—

1. In a folding bedstead, the combination, 5 with a standing frame provided with friction-plates rigidly secured thereto, of a movable bed-frame provided with friction-blocks that are adapted to bear against said friction-plates at every phase of the movement of said bed-
10 frame, as and for the purpose specified.

2. In a folding bedstead, the combination, with a standing frame, A, having friction-plates

E, rigidly secured thereto, of a movable bed-frame, B, having friction-blocks D, provided with adjusting-screws d, as herein described, 15 the said friction-blocks being adapted to bear against said friction-plates through every phase of the movement of said bed-frame, as and for the purpose specified.

CHARLES W. PEOBLE.
